UNITED STATES PATENT OFFICE.

ERNEST H. PEABODY, OF NEW YORK, N. Y.

OIL-BURNER FOR FURNACES.

No. 880,698.

Specification of Letters Patent.

Patented March 3, 1908.

Application filed March 19, 1906. Serial No. 306,924.

To all whom it may concern:

Be it known that I, ERNEST H. PEABODY, a citizen of the United States, residing in the city of New York, county and State of New York, have invented a certain new and useful Improvement in Oil-Burners for Furnaces, of which the following is a specification.

This invention has relation to a novel form of cheap and manageable burner for oil, intended for use in furnaces, under boilers and the like.

The principal feature of the invention is the novel arrangement of movable tip with suitable supply pipes, by use of which the tip is made adjustable or not at will and wherein, while easily removed or inserted, the tip is held as tightly in place as desired during use, to prevent leakage.

The invention is illustrated in the accompanying drawings in which

Figure 1 is a longitudinal median section of my device as used with an eccentrically mounted tip, Fig. 2 is a section of the tip on the plane X—X in Fig. 1 and Fig. 3 is a view 25 similar to Fig. 1 but showing a modification.

The principal feature of the invention consists in the use of a removable two-chambered tip with appropriate outlets between two abutting pipes for oil and steam respectively and means whereby the tip may be squeezed between the pipes to secure it in place.

The tip is shown at 1 and is preferably though not necessarily, cylindrical in form. 35 The cylinder, which is preferably made of steel, is divided across its middle by a partition 2 through which an opening 3 is bored which fits snugly around the fastening bolt 4.

The walls of the cylindrical tip 1 are provided on one side with appropriate outlets 40 above and below the partition 2. These preferably take the form of parallel slots 5 and 6 across the cylinder and one directly above the other.

45 The oil and steam enter respectively by the passages 7 and 8 in the main pipe 9 and these passages diverge by the two branch pipes 10 and 11 and finally turn so as to abut the one on one side of the tip 1 and the other 50 on the other side. While I prefer to use pipes 10 and 11 having openings with parallel faces, as shown, this is not essential to my invention.

The fastening bolt 4 passes down through 55 the final courses of the two branch pipes and its end is preferably threaded directly into

the body of one of said branch pipes. Any well known way of using this bolt is within my invention.

As shown in Figs. 1 and 2, the bolt 4 60 passes through an opening 3 in the septum 2 which is placed eccentrically with regard to the axis of the cylindrical tip. As shown in Fig. 2, the diameter of the tip equals that of the two abutting pipe ends, and on one or 65 both of these pipe ends lugs 12 and 13 are provided which closely embrace the tip 1 when in place. This construction is employed where it is not desired to intrust adjustment of the tips to the workmen using 70 the burner. It will be seen that, when once in place, the tip as shown in Figs. 1 and 2 cannot be turned, as its pivot is eccentric and the lugs embrace its sides. Thus used, the oil as it flows from the slot 5 is sprayed into 75 the combustion chamber by steam leaving the slot 6 in a pre-determined direction.

Where it is found desirable to give the operator latitude in regard to the direction of the flame, the construction shown in Fig. 3 80 may be employed. Here the bolt 4 passes substantially axially through the tip 1 and, when the bolt 4 is loosened sufficiently, the tip can be turned by the fingers in any desired position. With this form lugs 12 and 85 13 may or may not be used.

It is one advantage of the form of burner herein described that the direction of the flame may be made either adjustable or not, as desired, by a simple change in the location 90 of the bolt. A further advantage of the invention resides in the facility with which tips of this character are firmly secured in place while easily adjusted or removed by simply manipulating a single bolt.

95 Various changes may be made in this device without departing from the scope of the invention, and I am not to be understood as limiting myself to the details herein shown and described.

100 What I claim is—

1. An oil burner for furnaces comprising separate oil and steam conduits having mutually opposed openings, a tip having separate outlets for oil and steam located between 105 said openings and means for pressing the ends of said conduits together upon said tip, substantially as described.

2. An oil burner for furnaces comprising separate oil and steam conduits having mutually opposed openings, a tip having a cross 110 partition and slotted on each side thereof,

- said tip being located between said conduit openings, and means for pressing the conduit ends together upon said tip, substantially as described.
5. An oil burner for furnaces comprising a main conduit with two passages dividing into two branch conduits having mutually opposed openings, a tip located between said openings and means for pressing said branch conduits together on said tip, substantially as described. 20
6. An oil burner for furnaces comprising separate oil and steam conduits having mutually opposed openings, a cylindrical tip located between said conduit ends and a bolt passing through said conduit ends and said tip to draw said ends together, substantially as described. 25
7. An oil burner for furnaces comprising separate oil and steam conduits having mutually opposed openings, a cylindrical tip having a cross partition and located between said openings, a bolt passing eccentrically through said conduit ends and tip and means for preventing rotation of said tip around said bolt, substantially as described. 30

ERNEST H. PEABODY.
